(57) **CLAIM**

The ornamental design for a faucet valve body, as shown and described.

DESCRIPTION

FIG. 1 is a front, top and right-side perspective view of the faucet valve body showing my new design;
FIG. 2 is a front elevation view thereof;
FIG. 3 is a rear elevation view thereof;
FIG. 4 is a left side view thereof;
FIG. 5 is a right view thereof;
FIG. 6 is a top plan view thereof;
FIG. 7 is a bottom plan view thereof; and,
FIG. 8 is a rear, bottom and left-side perspective view thereof.

The broken lines throughout the drawing figures depict portions of the faucet valve body that form no part of the claimed design.
